(57) **CLAIM**

The ornamental design for panel for sound absorption, as shown and described.

DESCRIPTION

The patent or application file contains at least one drawing executed in color. Copies of this patent or patent application publication with color drawing(s) will be provided by the Office upon request and payment of the necessary fee.

1. Panel for sound absorption

1.1 : Perspective

1.2 : Front

1.3 : Back

1.4 : Top

1.5 : Bottom

1.6 : Left

1.7 : Right

1.8 : Cross sectional

The present product is a panel for sound absorption used by attaching the product to a wall surface; the product has multiple holes on the surface; reproduction number **1.8** is a cross-sectional view along A-A line shown in reproduction number **1.4**; no protection is sought for the red-colored portion of the product; no protection is claimed for the color of the design; the design is transparent; the red color in the back view appears transparent in the perspective view, the front view, and the cross-sectional view along line A-A; however, the red color is omitted in such reproductions for convenience.
